(57) CLAIM

The ornamental design for a beverage container lid, as shown and described.

DESCRIPTION

FIG. 1 is a top perspective view of a beverage container lid showing my new design;

FIG. 2 is a front view thereof;

FIG. 3 is a right side view of the beverage container lid of FIG. 1;

FIG. 4 is a left side view thereof;

FIG. 5 is a rear view thereof;

FIG. 6 is a top view thereof; and,

FIG. 7 is a bottom view thereof.

The broken lines represent portions of the structure that form no part of the claim.
